UNITED STATES PATENT OFFICE.

HERMAN M. BIEBEL, OF OAKMONT, PENNSYLVANIA, ASSIGNOR TO WESTINGHOUSE ELECTRIC AND MANUFACTURING COMPANY, A CORPORATION OF PENNSYLVANIA.

OVEN.

Application filed February 8, 1923. Serial No. 617,765.

To all whom it may concern:

Be it known that I, HERMAN M. BIEBEL, a citizen of the United States, and a resident of Oakmont, in the county of Allegheny and State of Pennsylvania, have invented a new and useful Improvement in Ovens, of which the following is a specification.

My invention relates to ovens and particularly to electrically-heated ovens.

The object of my invention is to provide a relatively simple, compact, easily manufactured and easily assembled electrically-heated oven for heat treating materials.

In practicing my invention, I provide a plurality of plane heat-insulating panels which are so mounted relatively to each other as to enclose an oven chamber that is of substantially rectangular form in longitudinal section and of substantially square form in lateral section. A shaft is rotatably mounted in the oven structure and carries a plurality of circular material-supporting means.

Electric heating elements are located in the corners of the oven structure closely adjacent to the outer periphery of the material-supporting means and are of arcuate contour in lateral section. Suitable reflecting means are located back of the respective heating elements.

Baffle plates are mounted on the oven structure and extend from the inner surfaces of the respective walls to within a short distance of the shaft.

In the drawings,

Figure 1 is a view, in vertical section, of an oven embodying my invention,

Fig. 2 is a view, in horizontal section therethrough, taken on the line II-II of Fig. 1, and

Fig. 3 is a view, in horizontal section therethrough, taken on the line III-III of Fig. 1.

An oven structure 10 comprises a skeleton supporting frame 11 which is provided with a plurality of suitable supporting members 12. An intermediate plate 13 may be employed to stiffen the skeleton structure and also serve as a support for an operating means.

A plurality of heat-insulating wall panels 14, comprising the side and rear walls, each comprise inner and outer metal sheets spaced apart by a suitable thickness

of heat-insulating material. The specific construction of the heat-insulating walls forms no part of my invention, and is, therefore, not further described or illustrated in detail. The side and rear panels 60 may be suitably secured together at their edges by angle bar members 15 or by any other suitable or desired construction which will operate with the heat insulating panels to form a sufficiently rigid oven structure. 65

A relatively narrow front panel 16, that co-operates with a door panel 17 to enclose the front of an oven chamber 18, a top heat insulating panel 19, and a bottom heat insulating panel 21, are provided to co-operate 70 with the side and rear wall panels to totally enclose the oven chamber 18.

The panels 14 are substantially rectangular in contour and of plane construction and the width of the two panels 16 and 17 is 75 substantially the same as the width of one of the panels 14, whereby the lateral section of the oven chamber 18 is of substantially square form.

Suitable hinge members 22 connect the two panels 16 and 17 to permit of opening and closing the door panel 17, a handle member 23 and a suitable latching means 24 being provided, which parts may be of any suitable or desired construction usually employed in the art. 80

A shaft 25 is located centrally of the chamber 18 and is rotatably mounted in bearing members 26 and 27 located respectively in the panels 19 and 21. The shaft 90 25 extends through the lower heat-insulating panel 21 and therebeyond and has mounted thereon a worm 28 which is operatively engaged by a worm gear 29 mounted on the shaft of a suitable driving means 31, here illustrated as an electric motor located on the plate 13 of the supporting means. A plurality of trays 32 are mounted on shiftable skeleton frames 33 that are located in spaced relation on the shaft 25. 100

If desired, the trays 32 may be of substantially circular contour and of unitary construction and be nonremovable from the supporting frames 33. The trays 32 may, however, be made segmental in construction and be removable from the supporting frames 33. In the latter case, I prefer to employ four arms in each of the supporting frames 33 in smaller ovens and a larger number of arms in relatively large ovens, 110

the number, of course, being dependent upon the material to be placed upon the respective segmental trays and the ease of removing and of inserting the same by the operator.

A plurality of electric heating elements 34, 35, 36 and 37, each of arcuate shape in lateral section and of any suitable or desired construction are located in the oven 10 chamber 18, in such position as to lie closely adjacent to the outer periphery of the material-supporting members 32. As hereinbefore stated, the heating elements may be of any suitable or desired construction, the 15 main consideration being that at least three of the heating elements, viz, those designated by the numerals 35, 36 and 37 shall each be of such arcuate extent as to cover substantially one-fourth of the periphery. 20 As it is necessary to remove the material through the opening provided by the hinged door panel 17, the heating element 34 is made of relatively small arcuate extent. The capacities of the heating elements 35, 25 36 and 37 may be of respectively increasing value, that is, the amount of heat generated by the heating element 34 is relatively small because of its small size, the amount of heat generated by the element 35 is larger and 30 the amount of heat generated by the element 37 is the maximum for the series.

Each of the heating elements extends substantially from the bottom to the top of the oven chamber 18. Reflector members 38, 35 also of arcuate form in lateral section, are placed back of the respective heating elements, are substantially co-extensive therewith, and reflect a portion of the heat rays therefrom, against material which is placed 40 upon the trays 32.

A plurality of baffle plates 39 extends inwardly from the respective panels 14 and 16 and are here shown as four in number, although any suitable number may be employed in order to provide any plurality of compartments within the oven chamber 18 that may be maintained at different temperatures, if required by the heat treating processes to which the materials are to be 45 subjected. The baffle plates 39 serve also to restrict and to reduce the cooling effect of the opened door 17 when materials are removed from or placed within the oven chamber 18.

50 The oven embodying my invention may be employed for a variety of heat treating purposes. For instance, I may construct the oven as a bake oven for bread or pastry, in which case the shaft 25 extends in a vertical direction substantially as illustrated in the drawings. By varying the capacity of the heating elements and gradually increasing them, I am able to subject the materials placed on the material carrying means to a 55 gradually increasing temperature. If it is

desired to subject the material to decreasing temperatures, it is, of course, only necessary to reverse the direction of the shaft 25 and of the material-carrying means supported thereby.

70

The oven embodying my invention may also be employed for other purposes, such as core baking and where it is necessary to bake a large number of the same type of cores, the width of the baffle plates 39 may 75 be made such as to just permit the material to move therebelow during the rotation of the shaft 25 and if the baffle plates 39 extend upwardly relatively close to the under surfaces of the material-carrying means, a 80 sufficient separation of the oven chamber into compartments is effected, which compartments may be maintained at different temperatures.

If it is desired to construct an oven in 85 which the shaft 25 extends in a horizontal direction, this may also be accomplished providing that the material-carrying means is suitably changed to permit of mounting thereon the material to be heat treated.

90 The device embodying my invention employs a plurality of plane heat insulating walls that are easily constructed and that are easily and quickly assembled. The material-carrying means located in the oven 95 chamber enclosed by the plane heat-insulating walls are of substantially circular contour and when located within the oven chamber 18, of substantially square shape in lateral section, permit of mounting within 100 the oven chamber in the corners thereof, heating elements of arcuate shape in lateral section, which heating elements occupy what is otherwise unused space within the oven chamber. In other words, by suitably selecting the dimensions of the substantially 105 circular material-carrying means, of the heat-insulating panels, and of the heating elements, I obtain a relatively compact oven structure, a plurality of which may be located in side-by-side relation or back-to-back relation, and will, therefore, occupy a minimum amount of floor space.

110 Various modifications and changes may be made herein without departing from the 115 spirit and scope of my invention, and I desire, therefore, that only such limitations shall be placed thereon as are indicated in the appended claims or are imposed by the prior art.

120 I claim as my invention:

1. In an oven, in combination, a plurality of heat-insulating panels enclosing a substantially rectangular oven chamber, means for moving material in a substantially circular path in said chamber, and a plurality of heating elements, of arcuate form, located in the corners of said chamber.

125 2. In an oven, in combination, an oven 130

chamber, of substantially rectangular shape, flat heat-insulating panels surrounding the same, means for moving material in a substantially circular path in said chamber and a heating element of arcuate form located in a corner of said chamber closely adjacent to said material moving means.

3. In an oven, in combination, a plurality of heat-insulating panels enclosing a substantially rectangular oven chamber, means for moving material in a substantially circular path in said chamber, and a plurality of heating elements, located in the corners of said chamber, said heating elements being of such form and extent as to lie closely adjacent to and outside of said path of travel and to cover the major portion thereof.

4. In an oven, in combination, a plurality of flat heat-insulating panels enclosing an oven chamber of substantially rectangular shape, means for moving material in a substantially circular path in said chamber, a plurality of heating elements, of arcuate form, located closely adjacent to and outside of said circular path and extending across the corner portions of said chamber, and reflector members, of arcuate shape, located outside of said heating elements.

5. In an oven, in combination, a plurality

of flat heat-insulating panels enclosing an oven chamber of substantially rectangular shape, means for moving material in a substantially circular path in said chamber, a plurality of electric heating elements of arcuate shape and of progressively increasing heating capacity, located circumferentially of said circular path in the corner portions of said chamber, and means in said chamber for restricting the heating effect of a heating element to a predetermined portion of said oven chamber.

6. In an oven, in combination, a plurality of flat heat-insulating panels enclosing an oven chamber of substantially rectangular shape, one of said panels having a door portion therein, means for moving material in a substantially circular path in said chamber, a plurality of electric heating elements, of arcuate form, located closely adjacent to said circular path and extending across the corner portions of said chamber, and means in said chamber for limiting the cooling effect of the opened door to a predetermined portion only of said chamber.

In testimony whereof, I have hereunto subscribed my name this first day of February, 1923.

HERMAN M. BIEBEL.
